UNITED STATES PATENT OFFICE.

FRANK A. BEAL, OF HAVERHILL, MASSACHUSETTS.

NAILING-MACHINE FOR BOOTS OR SHOES.

SPECIFICATION forming part of Letters Patent No. 333,812, dated January 5, 1886.

Application filed November 5, 1885. Serial No. 181,957. (No model.)

To all whom it may concern:

Be it known that I, FRANK A. BEAL, of Haverhill, county of Essex, and State of Massachusetts, have invented an Improvement in 5 Nailing-Machines for Boots and Shoes, of which the following description, in connection with the accompanying drawings, is a specification, like letters on the drawings representing like parts.

10 This invention has for its object to provide a nailing-machine with mechanism for uniformly feeding headed nails or tacks into a position below the driver, the headed nails being dropped singly into a nose or nail-tube 15 below the driver, after which they are driven singly.

In my improved apparatus the driver-bar, carrying the driver, is made to reciprocate through a feeding-cylinder arranged within a 20 tubular shell or case provided at its inner side with a spiral groove, the lower wall left by forming such groove serving as a support for the heads of the nails or tacks as they are fed from the upper end of the shell or case by 25 means of the feeding device, preferably made as a roller grooved longitudinally.

Figure 1, in side elevation, partially broken out, shows my improvement embodied in a nailing-machine adapted to be operated by 30 hand; but I desire it to be understood that the devices herein described, with slight alterations, may be adapted for use in power machines. Fig. 2 is a side elevation of the feeding device alone, the upper end of the 35 feeding device being partially broken away. Fig. 3 is an upper end view of the feeding device, together with a portion of the case or shell, the said figure showing three headed nails in the positions that they will occupy 40 when the machine is in operation. Fig. 4 is a side elevation, chiefly to show the case or shell and its nose, a portion of both the shell and nose being broken away. Fig. 5 is a top view of Fig. 4, and Fig. 6 is a detail of the 45 pawl for rotating the feeding device intermittently.

The feeding device—composed, preferably, of a long cylinder, A, provided with a series of grooves, a a, extended from end to end, and 50 a central longitudinal passage, a'—has at its upper end a ratchet-wheel, a². The case or

shell B, made as a cylinder, is grooved spirally at b, leaving surfaces 22, upon which may rest the flanges of the heads of nails or tacks n. The feeding device A is placed within the case 55 or shell B, with the lower end of the feeding device resting upon the nose C, having the driver-opening C', the lower end of the said opening receiving within it suitable nail-centering springs, c, which act, as usual, to keep 60 the point of the nail from descending too low before being struck by the driver. The upper end of the nose is provided with a flange, c², which is screwed or otherwise attached to the lower end of the case or shell. The case or 65 shell B receives within it the feeding device A, and is kept therein by the cap D, flanged to embrace the upper end of the case or shell, the said cap having a bearing, d, through which is extended the driver-bar E, having 70 secured to its lower end the driver e, the spiral spring e', surrounding the driver, and in practice resting at its lower end upon the metal block constituting the nose, acting against a shoulder, e², normally keeping the said driver- 75 bar in its elevated position, the lower end of the driver at such time being below the point f, (see Fig. 4,) where the hole in which the driver works intersects a diagonal passage, n³, which joins the lower end of the spiral groove 80 b with the driver-passage C'. The driver-bar E has at one side a straight groove, g, which receives a pin, g', of the collar d, the said pin preventing the rotation of the driver-bar and driver as the said driver-bar is made to reciprocate in one direction by pressure or by a blow against the knob g³ or by the spring e'. The driver-bar is also provided with a second groove, a portion of which is made cam-shaped, as at h. This cam-groove receives in it a pin, 85 h', extended through a collar, h², surrounding the driver-bar loosely. The collar h² has attached to it a pawl, h³, which is made to engage one and then the other tooth h⁴ of the feeding device. In the reciprocation of the 90 driver-bar the action of the cam-groove h upon the pin h' causes the collar h² to rotate, the pawl h³ at such time engaging the teeth h⁴ and rotating the feeding device.

Referring to Fig. 1, it will be noticed that 100 each headed nail or tack rests in a longitudinal space of the feeding-roll, and in that fig-

ure, as well as in Figs. 1 and 4, it will be noticed that the heads of the nails are supported by one of the flanges formed by the spiral groove *b* in the case or shell, and being so engaged and supported, substantially as shown in Fig. 3, the rotation of the feeding device enables the latter to act as a toothed surface with points between adjacent headed nails, thus positively feeding the said nails down along the said groove from the upper to the lower end of the case or shell.

I do not desire to limit my invention to the exact construction of feeding device herein shown and described, for instead of it I might 15 employ any other usual or well-known equivalent roller which would act to keep nails separated one from another and to push or carry the individual headed nails, one after the other, from the upper to the lower part of the annularly-grooved case or shell, discharging the same into the nose *C*, to be acted upon by the driver *e*. When the driver is in its lowest position, it covers the mouth of the opening *n*³, leading from the groove *b*, into the driver- 20 passage. The nails are permitted to pass from the groove *n*³ into the driver - passage only when the lower end of the driver is brought 25 above the point *f*.

I claim—

1. The spirally-grooved case or shell, combined with a rotating feeding device substantially such as described, to engage the headed nails supported by their flanges at the inner side of the said case or shell, as described, the feeding device effecting the gradual feeding of the headed nails from the upper to the lower end of the case or shell, substantially as described. 35

2. The case or shell provided with a spiral groove, the attached nose provided with a groove for the driver, and having a groove to lead the tacks from the spiral groove into the driver - groove, and the driver-bar, and the driver, combined with the rotating feeding device, grooved substantially as described, and 40 with a pawl to engage the ratchet-wheel upon and rotate the said feeding device, substantially as set forth. 45

In testimony whereof I have signed my name to this specification in the presence of two subscribing witnesses. 50

FRANK A. BEAL.
